UNITED STATES PATENT OFFICE

LEO KRESSER, OF SPRINGFIELD, MASSACHUSETTS, ASSIGNOR TO UNITED AMERICAN BOSCH CORPORATION, OF SPRINGFIELD, MASSACHUSETTS, A CORPORATION OF NEW YORK

HUMIDIFIER

Application filed September 2, 1932. Serial No. 631,482.

This invention relates to improvements in humidifying and ventilating apparatus; and especially to a humidifying appliance adapted to be employed in conjunction with a heater or radiator in dwellings, industrial establishments and other places for the purpose of moistening the air and maintaining the circulation thereof.

An object of the invention is to provide a device of simple construction, inexpensive to produce and operate, and easy to install at any convenient point, for the purpose of increasing the aqueous content of the atmosphere to the extent desired.

The objects and advantages of the invention are set forth in the accompanying description and drawing but the disclosure is illustrative only, and alterations in the shape, size and arrangement of the various parts may be made, without going beyond the principle of the invention or exceeding the scope of the appended claim.

On the drawing:

Fig. 1 is a side view, partly in section, showing apparatus according to this invention, mounted and in readiness for use;

Fig. 2 is a side elevation of the humidifier itself; and

Fig. 3 shows a modification of the device of Fig. 2.

The same numerals identify the same parts throughout.

The entire apparatus comprises a hood or cover 1 for a heater or radiator 2; and the hood supports a casing 3 in which the humidifying device is placed. This casing may be mounted on the top of the hood or the side, and the hood will be provided with an air inlet opening 4 and an outlet opening 5; with the casing so disposed that air flowing through the outlet 5 passes through the casing 3. Within the casing is an electric motor 6, the frame of which is carried by a post 7, and on the shaft 8 of this motor in the casing 3 is a fan 9. Between

the motor and the fan, and likewise secured on the shaft 8 to turn with same, is a cone-shaped distributor plate 10. Preferably the plate 10 is secured to the hub 11 of the fan between it and the adjacent bearing of the shaft 8.

Upon the frame of the motor is a bracket 12 to which is made fast the end of a water supply pipe 13. The edge of the plate is bent out in a radial plane to form a flange as shown at 14, and the end of the pipe 13 is bent down to deliver water upon the conical surface of the plate 10, between the hub 11 and the flange 14. Hence, as the fan and plate revolve, the water flowing down on the plate 10 towards the shaft 8 will be impelled by centrifugal force towards the flange and thrown outward in finely divided particles to be taken up by the air drawn through the casing 3 by the fan and spread throughout the atmosphere of the room in which the apparatus is situated.

If desired, the water supply pipe may be arranged to deliver to the concave side of the distributor 10, as shown on Fig. 3, where the bracket 15 mounts the end 16 of the supply pipe in position to discharge the water against the plate 10, near the center thereof. The operation of this form is of course the same.

The casing 3 may have a trough or groove 17 therein, to collect the drip from the plate 10 and allow it to drain out through a pipe 18. The pipes or conduits 13 and 18 can be provided with suitable valves or stopcocks, and the pipe 13 may be connected either to a city water pipe or spigot, or to a small pump driven from any available source of power. The water may be used over by pumping it back to the casing 3.

The apparatus is therefore quite simple and capable of being operated at little cost. It will make an ordinary radiator heat much more than the usual space served by the radiator. It can of course be utilized with or

without a heater or radiator, since the fan and distributor plate make a complete unit which can be set up anywhere and connected to operate in the manner required. The device not only moistens air but also keeps it circulating, thus insuring a complete supply of fresh moist air as it may be needed, and at a temperature which of course can be controlled by regulating the heater itself.

10 Having described my invention, what I claim to be new and desire to secure and protect by Letters Patent of the United States is:

15 A humidifying device comprising a heater, a hood thereover, the hood having an inlet and an outlet opening, a casing surrounding the outlet opening on the exterior of the hood, a motor in said casing, the motor having a shaft, a fan on said shaft, a cone-shaped 20 distributor plate between the motor and the fan, said plate presenting its convex side towards the fan, said fan and motor being so disposed that the fan and the distributor plate are between the motor and the heater, 25 a bracket on the motor, and a supply pipe held by the bracket to deliver water upon the convex surface of the plate.

In testimony whereof I affix my signature.
